UNITED STATES PATENT OFFICE.

WILLIAM H. McCLELLAND, OF HUNTINGDON, PENNSYLVANIA, ASSIGNOR, BY MESNE ASSIGNMENTS, TO ROY P. M. DAVIS, OF MOUNT UNION, PENNSYLVANIA.

SANDING DEVICE.

Application filed December 15, 1924. Serial No. 755,941.

My invention relates to improvements in brick making machines and is more particularly directed to that type of machine where in the green bricks are formed in independent molds, each of which is conveyed past a filling and discharging station.

The object of my invention is to provide means for coating the interior of each mold with sand or similar granulated material to prevent the newly formed brick from adhering thereto and breaking when in the act of removing the same from the mold.

A further object of my invention is to provide means of the class described, so positioned in the line of travel of the molds from their discharging to filling positions that they are received and treated successively and continuously.

Another object of my invention is to provide means for operating the sanding device in unison with the mold conveying means.

These and other objects will be fully apparent from the following description.

In the accompanying drawings:—

Figure 1 is a side elevation of my improved sanding device illustrating the upper portion thereof which is directed to the operating means.

Figure 1^a is a similar view showing the lower portion of the device and more specifically the sanding means.

Figure 2 is a vertical sectional view taken through the center of the sanding means.

Figure 3 is a detail view of the means for locking the sanding means in its receiving and discharging positions.

Figure 4 is a top plan view of the locking means.

Figure 5 is a vertical sectional view taken on the line 5—5 of Figure 4.

Figure 6 is an end elevation of the locking means.

Figure 7 is a longitudinal sectional view of the same.

Figure 8 is a bottom plan view of Figure 7.

Figure 9 is a side elevation of the lower.

Figure 10 is an end elevation of the same.

Figure 11 is a top plan view of the locking operating device.

Figure 12 is a sectional view taken on the line 12—12 of Figure 11.

Figure 13 is a sectional view taken on the line 13—13 of Figure 11, and

Figure 14 is a detail view of the stub shaft upon which the locking means is mounted.

According to my invention, I provide means for coating the interior of a brick mold with sand or the like, the same consisting of a sand retaining hopper in which is mounted for rotation a mold carrying element, the same receiving a mold to be treated and upon rotation the element deposits upon the mold sand. The element is locked in its receiving and discharging positions by means of a locking device A, the same being moved by a cam engaging roller B, through the medium of a lever C and a connecting rod D. It is my purpose to operate the locking means in unison with the mold carrying means so that the locking means will be operative during the receiving and discharging periods of the mold carrying element.

Referring to the accompanying drawings in detail, wherein like reference characters denote corresponding parts throughout the several views, the numeral 1 indicates suitable vertically extending angle bars of a brick making machine, the same not being shown in the drawings, said bars having connected thereto my improved sanding device and the means for operating the same. It is of course to be understood that the sanding device which I will hereinafter describe will be mounted upon the brick machine in such a manner that it may readily treat the molds as they pass back to their filling station, and the power for operating the device may be obtained from the machine. The operation of the sanding device is continuous and treats the molds successively as they pass therethrough on their way back to the filling station.

As disclosed in Figure 2, the sanding device consists of a semi-cylindrical hopper 2 adapted to receive therein the molds to be treated and preferably of a width sufficient to receive therein a mold. The hopper 2 is made of sheet metal or the like and is suit-

ably reinforced, the lower portion having a discharge opening 3 whereby the sand within the hopper may be removed. The ends of the hopper 2 have mounted thereon suitable bearings, not shown, which receive therein a shaft 4, the same extending longitudinally of the hopper and adapted for rotation within its bearings.

One end of the shaft 4 has keyed thereto a sprocket wheel 5 around which passes a chain 6 leading from suitable driving means carried by the bars 1 and operated from the main drive of the brick machine.

It is my purpose to provide a driving means which will periodically rotate the shaft 4, and the sanding device carried thereby, the latter hereinafter described, and to this end I have arranged a driving means of the mutilated gear type which operates a shaft having keyed thereto a gear 7, around which the sprocket chain 6 passes.

That portion of the shaft 4 which extends over the hopper 2 is flattened, as indicated at 8, and has secured thereto plates 9 which extend approximately the entire length of the hopper 2. The plates 9 form a support for the molds H during the operation of the device, and they have secured therebetween, adjacent the ends of the hopper, upwardly and downwardly projecting hook members 10, being arranged in pairs and the upper and lower member at each end of the plates being in the same vertical plane, as illustrated in Figure 2. Each pair of the upper and lower hook members are connected by a metallic covering 11, the end portions of which extend down to form side flanges 12, thus forming a scoop like structure. Each covering 11 has riveted thereto, between the hook members a guard 13 the lower portion of which extends out at an angle to fall within the same vertical plane as the lip or edge of the other scoop member. The purpose of the guard member 13 being to assist in limiting the inward movement of the molds upon the plates 9 and at the same time to prevent the sand as it falls from the upper scoop from falling into the hopper by directing it into the lower scoop.

The side flanges 12 are adapted to receive thereon the molds to be treated, the same being received, as illustrated in Figure 2, upon the edges of the flanges.

In order to permit the entry of the molds to be treated into the hopper 2, one side wall of the hopper is provided with an opening 14 through which the molds pass. As hereinabove explained, the molds are received upon the edges of the flanges 12, and are limited in their inward movement by rods 15 connecting the hook members of each pair and against which the molds abut. Upon referring to Figure 2 it will be noted that the inclined guards 13 pass over the rods 15 and form thereunder, and between the hook

members 10 of each pair, an opening through which sand passes, in a manner hereinabove described. In order to prevent the sand from passing through this opening during the rotary movement of the scoops from their lower to their upper positions, it is my purpose to utilize the mold carried by the scoop as the means for closing this opening. This feature I consider to be a very important one in that the movement of the sand is controlled by the presence of a mold to be treated. Heretofore, I have used in actual practice sliding or hinged gates to control this movement of the sand but found these to be impracticable due to the difficulty of giving to the gate a free action as the same is at periods submerged in sand.

From the foregoing description it will be apparent that as the shaft 4 is rotated the upper scoop member will move down into the hopper 2, picking up a portion of the sand therein, and is then locked in a position so that the incoming mold H to be treated may be received upon the flanges 12. After the mold is received the shaft 4 again rotates and moves the scoop to its upper position, the sand being prevented from falling through the opening at the rear of the scoop by the mold which closes the same. Upon the scoop assuming its upper position the sand contained therein will drop down upon the mold, and that portion of the sand contained within the front portion of the upper scoop will drop and fall upon the guard 13 where it is carried to the lower scoop. As the scoop moves from its upper position the sand remaining therein will likewise be directed to the lower scoop by the guard 13. It is of course apparent that as the mold is removed from the scoop after having been treated it will draw the excess sand remaining upon the plate 9 toward the front where it will fall upon the guard 13 and be conveyed into the lower scoop. While the treated mold is being removed therefrom an untreated mold is being received within the lower scoop.

While I have not disclosed means for delivering or removing the molds to and from the device it is of course to be understood that any suitable means may be employed; for instance, endless conveyors or the like.

In order to prevent the sand within the scoops from being thrown out of the limits of the hopper when the scoops assume their upper positions, I have provided a shield 16 fixed to the edge of the hopper 2, the same being provided with an opening through which the treated molds pass out.

In order that the scoops may be locked in receiving and discharging positions, I have provided a locking device which I have indicated generally by the letter A and operated in a manner hereinabove referred to. The locking device A engages diametrically op-

posite notches provided in the periphery of the plate E, keyed to the shaft 4.

The locking device A consists of a threaded bolt 17 pivotally mounted upon a stub shaft 18, the latter being fixed to one of the bars 1. The bolt 17 is locked upon the shaft 18 by means of a pin 19 and spaced from engagement with the bar 1 by a shoulder 20 formed integral with the shaft 18.

10 The bolt 17 has slidably mounted thereon a casting 21, the opposite vertical side walls of which have fixed thereto, by bolts or the like 22, parallel and rearwardly extending bars 23, which receive therebetween a sliding block 24, the rear face of which abuts a nut 25 movable upon the bolt 17 and locked thereto by a pin 26.

The casting 21 is retained upon the bolt 17 by means of a second locked nut 25. Interposed between the casting 21 and the block 24, and coiled about the bolt 17, is a spring 27 which permits the backward movement of the casting upon the bolt 17.

25 The casting 21 has extending downward therefrom a bifurcated projection 28 which receives therein the periphery of a circular plate E keyed to the shaft 4, the base of the projection dropping into suitable notches 29 formed in the periphery of the plate, thus locking the shaft 4, and the sanding device carried thereby, in its several positions. It will be noted that the locking device as a unit is free to swing upon its pivotal connection with the stub shaft 18.

35 The upper face of the casting 21 is provided with spaced upwardly extending projections 30, the free end portions of which are connected by a bolt 31, upon which the lower end of a connecting rod D is mounted for pivotal movement. Thus it will be readily apparent that upon the movement of the connecting rod D the locking device A will be moved accordingly.

40 In order to prevent the block 24 from dragging upon the periphery of the plate E, the lower portion of the same is bifurcated, as indicated at 32, and rearwardly and downwardly tapered as indicated at 33.

The upper end of the connecting rod D is threaded and received within a threaded opening provided within a block 34, the end portions of which are reduced and squared, as at 35, to fit within openings provided within the end portions of side bars 36. The end portions 35 are further reduced and threaded, as indicated at 37, to receive thereon locking nuts 38 by which the bars 36 are retained in place.

45 The other end portions of the side bars 36 have positioned therebetween a roller 39 which has formed integral therewith upon each of its sides spacers 40, said roller and spacers being mounted for rotation upon a shaft 41, the end portions of which are threaded, as at 42, and project through suit-

able openings within the side bars to receive thereon locking nuts 43.

The roller 39 is free to rotate upon the shaft 41 and is adapted to engage a cam 44 formed upon the periphery of a wheel 45 keyed to a shaft 46, the latter being operated from any suitable power shaft of the machine. The side bars 36 are pivotally mounted upon a common pin 47 carried by a bracket 48 secured to one of the main bars 1.

50 Referring again to Figure 3, it will be noted that the plate E rotates in the direction of the arrow and before the notch 29 comes into position to be engaged by the locking device A, the same drops and rides upon the periphery of the plate E. In order to prevent the locking device from riding past the notch one wall of the latter is shorter than the other, as indicated at 29', thus permitting the other wall to serve as a 80 stop against which the locking device abuts, causing the same to drop into the notch.

55 From the foregoing, it is thought that the construction, operation and many advantages of the herein described invention will be apparent to those skilled in the art, without further description, and it will be understood that various changes in the size, shape and proportion, as well as minor changes in the details of construction, may be resorted to without departing from the spirit or sacrificing any of the advantages of the invention.

60 Having thus fully described my invention, what I claim as new, and desire to secure by Letters Patent, is:—

1. In a device of the class described, the combination of a material retaining hopper and a mold carrying element rotatable therein, means for periodically moving said element from a receiving to a discharging position, and a second means for locking said element in either of said positions.

in, driving means connected to said element for moving the same periodically from a receiving point to a discharge point, a second means alternating with the first said means for locking said element in either of said points, and said element adapted to deposit upon the mold carried thereby a portion of the material retained by said hopper.

5. In a device of the class described, 10 the combination of a sand retaining hopper and a mold carrying element rotatable therein, said element being composed of two scoop-like structures adapted to scoop up sand from the hopper during their rotation 15 and drop the same down upon a mold car-

ried thereby, and guide plates fixed to each scoop to guide therein a part of the sand dropped from the upper scoop.

6. In a device of the class described, 20 the combination of a sand retaining hopper and a mold carrying element rotatable therein, said element being composed of two scoop members being diametrically connected to a common shaft, a plate secured to each scoop to retain the sand therein during its movement, and said plate adapted to guide within one scoop a part of the sand dropping from the other scoop.

25 In testimony whereof I affix my signature.

WILLIAM H. McCLELLAND.
